UNITED STATES PATENT OFFICE.

ROBERT A. WALTON, OF LOS ANGELES, CALIFORNIA.

TELEPHONE-TRANSMITTER ATTACHMENT.

No. 823,090.

Specification of Letters Patent.

Patented June 12, 1906.

Application filed July 25, 1905. Serial No. 271,230.

To all whom it may concern:

Be it known that I, ROBERT A. WALTON, a citizen of the United States, residing at Los Angeles, in the county of Los Angeles and State of California, have invented new and useful Improvements in Telephone-Transmitter Attachments, of which the following is a specification.

This invention relates to telephone-transmitters; and the object thereof is to seal the transmitter temporarily from sound-vibrations at certain intervals during a conversation.

It is frequently desired by those using the telephone to converse with others in the office relative to certain matters, and oftentimes it is not desired to have the person at the other end of the line overhear the conversation carried on in the office. Under these conditions the person speaking does not desire to return the receiver to the hook, for the reason that the line would then be cut off. In cases where it is found desirable to close the transmitter all that can be done is to hold the hand over the transmitter-mouthpiece, which is not only extremely inconvenient, but oftentimes fails to accomplish the object.

It is the purpose of this invention to overcome these defects and to provide means for sealing the transmitters.

I attain these objects by means of the device described herein and illustrated in the accompanying drawings, in which—

Figure 1 is a central vertical section through a transmitter-mouthpiece, showing my device attached thereto. Fig. 2 is a face view of the transmitter with the mouthpiece removed therefrom. Fig. 3 is a central vertical section through the transmitter-mouthpiece, showing my modified form of attachment applied thereto. Fig. 4 is a face view of the modified form of the transmitter with the mouthpiece removed therefrom.

Referring now to the drawings, 5 is the mouthpiece of a telephone-transmitter, having the usual perforated screen 6 in place therein. This mouthpiece is secured in the circular detachable extension-sleeve 7 and consists of two members, the inner member 8 being connected to the face of the transmitter-case 9 and the outer member 10 being connected to the mouthpiece 5, both members being held in rotatable engagement with each other by a connecting-ring 11. The outer end of the inner member of this extension-sleeve is threaded externally, as at 12,

and is adapted to be secured in the aperture 13 in the face of the transmitter. On the outer end of the inner member of the extension-sleeve and on its inner perimeter and below the outer end I have provided a flange 14 to receive a perforated disk 15. This disk is preferably made of lead or other analogous material and has affixed to its outer surface a thin layer of felt 16 or other suitable material and is perforated, as at 17. The outer member is threaded internally, as at 18, for the reception of the transmitter-mouthpiece and is provided with an internal flange 19, in which a perforated disk 21 is secured, and an external beveled flange 20. This disk is similar to the one in the inner member, and its inner face is covered with felt 22 or other suitable material, and the perforations 23 are adapted to register exactly with the perforations 75 on disk 15 of the inner member. These two members are held in rotatable engagement with each other by the internally-threaded connecting-ring 11, which ring has an internal beveled flange 24 on its outer end. This beveled connecting-ring is provided with two stop-pins 25 and 26, which are secured to its outer face and are in the path of a pin 27, which projects from the side of the outer member of the extension and limits the 85 movement of the outer member against the inner member.

In Figs. 3 and 4 of the drawings I have illustrated a modified form of my invention in which the circular extension 28 consists of 90 but one member, which is secured to an aperture in the face of the transmitter-mouthpiece. On the inside perimeter of the extension is a flange 29, on which is seated a disk similar to that in my preferred construction 95 and having its outer face covered with felt. This disk has a central opening 30, which is adapted to be closed by a movable closure 31. This closure is slightly larger than the opening in the disk and is made of the same 100 material as the disk in the preferred construction and is covered with felt or other suitable material. Attached to this closure is a spring operating-handle 32, which projects through a slot 33 in the side of the extension 28.

In operation when it is desired to temporarily suspend the operation of the transmitter-circuit of a telephone the operator simply turns the mouthpiece of the telephone until the perforations on the disks are out of register with each other, the felt and lead of

which the disks are constructed effectually dampening the transmitter and preventing any sound-vibrations entering. I have also found that in constructing the disks of the above-described materials, which have the property of largely absorbing transmitted sound, it as effectually seals the transmitter as if the circuit was entirely cut out.

In the modified form shown in the last two figures of the drawings the operator simply pushes the disk-closure in engagement with the aperture in the disk mounted in the extension, the spring-handle keeping it in closed engagement, the slot in the extension-sleeve forming a bearing.

Having described my invention, what I claim as new, and desire to secure by Letters Patent, is—

1. In a device of the character herein described, a transmitter-seal composed of an outer and inner member, said outer member secured in movable engagement with the inner member and means secured to both members to seal the transmitter against sound-vibrations.

2. In a device of the character herein described, a transmitter-seal comprising an extension-sleeve mounted between the face of the transmitter and the mouthpiece, said extension-sleeve having means mounted therein to seal the transmitter against sound-vibrations; said means comprising a perforated disk secured to said extension-sleeve and adapted to register with like perforations in a disk mounted in the mouthpiece; said mouth-

piece in movable engagement with said extension-sleeve and adapted to rotate and close the perforations in the disk mounted in said extension-sleeve and seal the transmitter against sound-vibrations.

3. In a device of the character herein described, a transmitter-seal, comprising an extension-sleeve composed of an outer and inner member, said inner member secured to the face of the transmitter and having a perforated fabric-covered disk secured to its outer end; said outer member adapted to receive the mouthpiece and having a perforated fabric-covered disk, the perforations in said disk registering with like perforations in the disk secured to the inner member; means to hold the outer member in movable engagement with the inner member.

4. In a device of the character herein described, a transmitter-seal, comprising an extension-sleeve, said sleeve mounted between the face of the transmitter and the mouthpiece; a fabric-covered disk having an aperture therein, movable closure means attached to said extension-sleeve adapted to close the aperture in said disk and seal the transmitter against sound-vibrations.

In witness that I claim the foregoing I have hereunto subscribed my name this 19th day of July, 1905.

ROBERT A. WALTON.
